UNITED STATES PATENT OFFICE.

HORACE B. FAY, OF SHAKER HEIGHTS, OHIO.

METHOD OF MAKING METALLIC BELLows.

Application filed October 28, 1924. Serial No. 746,331

The present invention relates to a method of making deeply corrugated, flexible, tubular metal walls or metallic bellows, and more particularly to an improved method of 5 making such bellows by combined mechanical and fluid pressure operations to produce a superior bellows and one having substantially uniform wall thickness and temper throughout each portion of the corrugation. 10 To the accomplishment of the foregoing and related ends, said invention, then, consists of the means hereinafter fully described and particularly pointed out in the claims.

The annexed drawing and the following 15 description sets forth in detail one method and one product exemplifying my invention, such disclosed procedure and product constituting, however, but one of various applications of the principles of my invention.

20 In said annexed drawing:

Fig. 1 is a longitudinal central section through a tube showing co-operative rolls in position to form a partial corrugation in the wall of such tube; Fig. 2 is a longitudinal section showing one wall of a tube after 25 formation into corrugations by means of a collapsible die; and Fig. 3 is a longitudinal section through a portion of bellows formed by my improved method.

30 Metallic bellows may be manufactured either by rolling corrugations into the wall of the tube or by expanding the wall of a tube by fluid pressure exerted within the tube to produce externally extending corrugations, 35 or by a combination of these two methods in which the corrugations are first partially formed in the tube wall by fluid pressure and are then brought to their final form by mechanical operations, such as rolling. The 40 last-named process, that is, the combination which includes fluid pressure expansion followed by mechanical expansion or rolling, has the disadvantage of the usual rolling method, which is that tiny particles of grit 45 cling to the surface, either of the rolls or of the tube, and are rolled into the tube wall during the rolling operation, tending to make the tube weak at that point and liable to breakage when any extreme pressure is 50 applied to it.

The one particular advantage of bellows made by a fluid pressure process is that the 55 resistance of the bellows is tested during their formation, that is, the pressure necessary to expand the tube wall into corrugations is usually higher than any pressure

which is applied to the corrugations in actual service later, and also in the fluid pressure method there is no possibility of grit becoming embedded in the wall of the corrugations and weakening these walls.

The principal object of the present invention is the provision of a method which will combine the advantages of both the mechanical and fluid pressure methods, while retaining all of the advantages and characteristics given to the bellows by the fluid pressure method, which are the economy of manufacture, the testing of the bellows during its final formation under high pressure, and 70 the uniform stretching of the metal in each corrugation, which tends to make the corrugations of uniform strength and resiliency.

I make my improved bellows by first subjecting a relatively thin tubular wall to the 75 mechanical action of co-operative rolls disposed on opposite sides of the tube wall, as shown in Fig. 1. In this figure the tube wall 1 is mounted between a pair of rolls 2 and an opposed roll 3, the rolls 2 and 3 being movable toward and away from each other. In operation the tube is first positioned over the rolls 2, after which either the tube, containing the spaced rolls 2, is moved toward the roll 3 or the roll 3 is 80 moved up against the wall of the tube opposite to the space between the rolls 2, and is thus caused to form an encircling groove 85 or corrugation 4 in the tube wall.

A series of corrugations is formed in the 90 tube wall in the manner described, the corrugations being equally spaced and being of course parallel and at right angles to the axis of the tube. The tube, with its inwardly extending corrugations may then be expanded between these corrugations to provide complete exteriorly and interiorly extending corrugations by the application of fluid pressure within the tube, while supporting the previously formed inward corrugations against expansion. This operation may be performed in apparatus of the character described and claimed in the patent to F. K. Bezzenger, No. 1,506,966, dated September 2, 1924, in which a tube is 95 disposed within a partible die, each half of which includes a series of half rings or dies which, in the closed position of the die, completely encircle and engage against the wall 100 of the tube. In Fig. 2 I have shown a tube wall 1 provided with inwardly extending corrugations 4 engaged within die rings 5

and 6 of the type shown in the above-named patent. In this case, however, the rings 5 and 6 are constructed to enter and engage snugly against the previously formed inner corrugations.

After the tube has been so disposed within the die rings fluid pressure is exerted within the tube and acts to expand the portions of the tube wall lying between the rings 10 outwardly, while at the same time an increasing pressure is applied longitudinally of the tube to collapse the same, the rings being collapsed or brought together at the same time so that the outwardly extending corrugations which are in process of formation are concluded against the rings 5 and 6, which, at the finish of the operation, are in the relation shown in Fig. 2 at the upper part of the figure. In this way the entire corrugation is formed, each corrugation consisting of the previously formed inner portion 4 and the outward portion 7, the corrugations having parallel radial portions 8.

In producing a bellows in this manner it should be remembered that there may be not only a stretching of the metal produced by increasing the length of that portion of the tube measured longitudinally which is being corrugated, but also that this portion of the tube wall is being stretched also by the increase in diameter, that is, there is both a longitudinal and a circumferential stretch given to the metal. It will be apparent that the circumferential stretch will be different when the corrugations are thrown inward and the diameter reduced from the stretch imparted to a corrugation which is thrown outwardly, and I so proportion the initially formed inward corrugation and the subsequently formed outward corrugation that the stretch which is thus given to the metal is substantially the same, which will provide a uniform temper in both the crests of the inner and outer corrugations. The temper in the metal in the radial planes 8 is also substantially the same as that at the crests of the corrugations, since in a bellows made by a single fluid pressure operation, it has been found, the metal will flow and the stretch will be distributed throughout the entire corrugation very much more evenly than is possible when a tube wall is corrugated between rolls which merely stretch the portion of the metal lying between the crests of the spaced rolls.

The distribution of metal from the two operations is shown in an exaggerated way in Fig. 3, in which the thickest portion of the wall of the corrugation is at the points 9, which correspond to the points 10 in the tube in the condition shown in Fig. 1. The wall is, however, but little thicker at this point than elsewhere and is far more uniform than in bellows made by rolling methods.

It is also desirable in the formation of a

bellows by the present method to prevent any increase in the surface length of the bellows measured along a line lying on the surface of a tube or bellows and disposed parallel with the axis of the same, as it has been found that if the tube is materially lengthened in this dimension this lengthening is produced by undue stretching of the metal in the outer corrugations, which would impart too great hardness and temper to the 70 walls at these points and cause their early breakage. It will of course be apparent that in the initial mechanical step of the present method the tube length is increased somewhat, and it is therefore desirable to actually 75 shorten the tube length in the fluid pressure operation by an amount which substantially equals the increase in the first operation.

By the present method bellows having very deep corrugations may be made, since 85 different portions of the metal wall are formed into the inner and outer portions of the corrugation, that is, the metal is at no point stretched as much as is the case when the corrugation is formed entirely outwardly, 90 (as is the case of bellows made by a single fluid pressure expansion). In the first step of my method the metal may be stretched inwardly an amount producing the maximum safe working temper in this portion, 95 say 20% to 40%, after which other portions of the tube are stretched outwardly until the same maximum temper is there present, but in this second operation the previously stretched or tempered metal of the inner portion of the corrugation is not again stretched or subjected to any tempering action. The obvious advantage of this 100 method is the application of the fluid pressure method to the production of deep, evenly tempered corrugations which is a type of corrugation not otherwise possible with use of a fluid pressure operation, at least without subsequent rolling operations with the risks of introducing imperfections into the 105 metal wall.

The advantages of the present product are the uniformity of the wall thickness and temper throughout the entire area of each corrugation, and the consequent longer life 115 of the bellows in service, together with the fact that as the bellows is finished in a fluid pressure operation, which involves the establishment of a relatively high pressure within the bellows, it is thus possible to automatically test each bellows during its manufacture, and any bellows which will withstand this pressure will of course withstand the same or lower pressures in service. In addition to this advantage the completion of the bellows in a fluid pressure operation avoids any possibility of mechanically working into the walls of the corrugations particles of grit which would reduce thickness 120 at these points and tend to shorten the life 130

of the bellows and its resistance to leakage at high pressures. A still further advantage of the present method over the rolling method, which is most commonly practiced, is that it avoids the danger of either cutting through or materially reducing the thickness of the tube wall at the crests of the corrugations, which has been a common cause of failure with bellows manufactured by 10 mechanical or rolling methods.

Other forms may be employed embodying the features of my invention instead of the one here explained, change being made in the form or construction, provided the elements stated by any of the following claims 15 or the equivalent of such stated elements be employed, whether produced by my preferred method or by others embodying steps equivalent to those stated in the following 20 claims.

I therefore particularly point out and distinctly claim as my invention:—

1. In a method of making metallic bellows, the steps which consist in forming 25 spaced inwardly extending shallow grooves in a cylindrical metal wall, and then expanding such wall outwardly between such grooves by the application of pressure uniformly against the surface of said wall while 30 supporting the outer surfaces of such grooves against expansion.

2. In a method of making metallic bellows, the steps which consist in forming spaced inwardly extending shallow grooves 35 in a cylindrical metal wall, and then applying an internal fluid pressure against such wall while supporting the outer surfaces of such grooves against expansion.

3. In a method of making metallic bellows, the steps which consist in forming spaced inwardly extending corrugations 40 in a cylindrical metal wall, and then applying an internal expansion fluid pressure against such wall while supporting the outer surfaces of said inwardly extending corrugations against expansion during the expansion of the wall portions between said first-named corrugations.

4. In a method of making metallic bellows, the steps which consist in forcing 45 spaced portions of a tubular metal wall inward to an amount inducing the maximum safe working temper in the crest of the corrugation thus formed, and then expanding 55 the tubular wall between said first-named inner corrugations by the application of fluid pressure to form outwardly extending corrugations between said first-named inner corrugations.

5. In a method of making metallic bellows, the steps which consist in forcing spaced 60 portions of a tubular metal wall inward to form inwardly extending corrugations therein, and then expanding the wall outwardly 65 between such internally extending corruga-

tions by the application of fluid pressure within such tubular wall to an amount inducing the maximum safe working temper in the crests of the outer corrugations thus formed.

6. In a method of making metallic bellows, the steps which consist in forcing spaced portions of a tubular metal wall inward to an amount inducing the maximum safe working temper in the crest of the corrugation thus formed, and then expanding the wall outwardly between such inwardly extending corrugations by the application of fluid pressure to an amount inducing the maximum safe working temper in the crests of the outer corrugations thus formed.

7. In the method of making metallic bellows, the steps which consist in forming spaced inwardly extending shallow corrugations in a cylindrical metal wall, and then expanding such wall outwardly between such corrugations by the application of pressure against the surface of said wall.

8. In a method of making metallic bellows, the steps which consist in forcing spaced portions of a tubular metal wall inward to form inwardly extending corrugations therein, and then expanding the tubular wall between said first-named inner corrugations to form outwardly extending corrugations between said first-named inner corrugations.

9. The process of making bellows consisting in providing a tube of thin metal, forming a series of inwardly pressed spaced-apart annular grooves in and around said tube with connecting sections of said tube between said grooves, and then acting upon said grooved tube to form it into a flexible longitudinally expandible and contractible bellows.

10. The process of making bellows consisting in providing a plain elongated tube having a thin wall, rolling a series of spaced-apart inwardly extending annular grooves with unworked and unchanged connecting sections of said tube between the grooves having the diameter of said tube, and then working said connecting sections to form outwardly extending corrugations from said connecting sections.

11. The process of making bellows consisting in providing a plain elongated tube having a thin wall, forming a series of spaced-apart inwardly extending annular grooves therein with uncorrugated connecting sections of said wall between the grooves, and then subjecting said connecting sections to operations which form outwardly extending corrugations from said connecting sections.

12. The process of making bellows consisting in providing a tube of thin metal, forming a series of inwardly pressed spaced-apart annular grooves in and around

- said tube with connecting sections having the diameter of the tube between said inwardly pressed grooves, and then forming said connecting sections into outwardly extending corrugations.
13. The process of making bellows consisting in providing a thin walled metal tube, rolling the metal of the tube inward to form grooves with connecting portions having the same diameter as the tube between said grooves, and forming said connecting portions into outwardly extending corrugations while enlarging the diameter of the same.
14. The process of making bellows consisting in providing a thin walled metal tube, rolling a consecutive series of spaced-apart grooves inwardly in said tube toward the axis of the tube with unworked connecting portions of the tube between said grooves, and forcing said connecting portions outwardly to form outwardly extending corrugations.
15. The process of making bellows consisting in providing a thin walled metal tube, consecutively forming in said tube a series of spaced-apart inwardly directed grooves which are connected by sections having substantially the same diameter as the original tube, and then working said connecting sections outwardly to form outwardly extending corrugations.

Signed by me, this 25 day of October, 1924.

HORACE B. FAY.

DISCLAIMER

1,644,823.—*Horace B. Fay, Shaker Heights, Ohio.* METHOD OF MAKING METALLIC BELLOWS. Patent dated October 11, 1927. Disclaimer filed October 17, 1935, by the assignee, *The Fulton Sylphon Company*.

Hereby enters this disclaimer to that part of the claims in said specification which is in the following words, to wit:

“1. In a method of making metallic bellows, the steps which consist in forming spaced inwardly extending shallow grooves in a cylindrical metal wall, and then expanding such wall outwardly between such grooves by the application of pressure uniformly against the surface of said wall while supporting the outer surfaces of such grooves against expansion.

“2. In a method of making metallic bellows, the steps which consist in forming spaced inwardly extending shallow grooves in a cylindrical metal wall, and then applying an internal fluid pressure against such wall while supporting the outer surfaces of such grooves against expansion.

“3. In a method of making metallic bellows, the steps which consist in forming spaced inwardly extending corrugations in a cylindrical metal wall, and then applying an internal expansion fluid pressure against such wall while supporting the outer surfaces of said inwardly extending corrugations against expansion during the expansion of the wall portions between said first-named corrugations.”

“7. In the method of making metallic bellows, the steps which consist in forming spaced inwardly extending shallow corrugations in a cylindrical metal wall, and then expanding such wall outwardly between such corrugations by the application of pressure against the surface of said wall.

“8. In a method of making metallic bellows, the steps which consist in forcing spaced portions of a tubular metal wall inward to form inwardly extending corrugations therein, and then expanding the tubular wall between said first-named inner corrugations to form outwardly extending corrugations between said first-named inner corrugations.

“9. The process of making bellows consisting in providing a tube of thin metal, forming a series of inwardly pressed spaced-apart annular grooves in and around said tube with connecting sections of said tube between said grooves, and then acting upon said grooved tube to form it into a flexible longitudinally expandable and contractible bellows.

“10. The process of making bellows consisting in providing a plain elongated tube having a thin wall, rolling a series of spaced-apart inwardly extending annular grooves with unworked and unchanged connecting sections of said tube between the grooves having the diameter of said tube, and then working said connecting sections to form outwardly extending corrugations from said connecting sections.

“11. The process of making bellows consisting in providing a plain elongated tube having a thin wall, forming a series of spaced-apart inwardly extending annular grooves therein with uncorrugated connecting sections of said wall between the grooves, and then subjecting said connecting sections to operations which form outwardly extending corrugations from said connecting sections.

“12. The process of making bellows consisting in providing a tube of thin metal, forming a series of inwardly pressed spaced-apart annular grooves in and around said tube with connecting sections having the diameter of the tube between said inwardly pressed grooves, and then forming said connecting sections into outwardly extending corrugations.

“13. The process of making bellows consisting in providing a thin walled metal tube, rolling the metal of the tube inward to form grooves with connecting portions having the same diameter as the tube between said grooves, and forming said connecting portions into outwardly extending corrugations while enlarging the diameter of the same.”
